PUMP

Alexander V. Mueller, Salem, Ohio, assignor to
 The Deming Company, Salem, Ohio, a corporation of Ohio

Application January 11, 1944, Serial No. 517,775

8 Claims. (Cl. 103—113)

This invention relates to a self-priming pump of the type where some of the discharged liquid is returned to the suction side of the pump to effect the priming and there is automatically acting means to shut off such returning liquid when no longer needed.

The general object of the invention is to provide a self-priming pump having discharge and suction passageways with a communication between such passageways, extraneously of the impeller, closed during the normal operation of the pump but available whenever necessary to supply priming liquid to the impeller independent of the relative pressures in such passageways. To this end, I have so arranged my pump that the recirculation of liquid is controlled by the fluid pressure in the discharge passageway and is independent of the pressure in the inlet passageway, whether the pump has been standing and its operation just started or whether it loses its prime during operation.

A further and particular object of the invention is to devise a self-priming pump with a control of such character, and so connected for operation, that stopping of the recirculation shall not be affected by vacuum or reduced pressure in the suction conduit to the impeller but shall take place equally well with slight or great negative pressure in such conduit.

Other objects and features of the invention will be apparent from the following description of a preferred embodiment of the invention illustrated in the drawings.

In the drawings, Fig. 1 is a vertical axial section of a centrifugal pump having my priming control; Fig. 2 is a vertical section thereof through the discharge passageway and looking toward the impeller, as indicated by the line 2—2 on Fig. 1; Fig. 3 is an axial section of the controlling device illustrated in Fig. 1 but showing it in the closed position; Figure 4 is a radial section of the controlling device taken on the line 4—4 of Figure 3 looking in the direction of the arrows.

As shown in Fig. 1, 10 designates a suitable pump frame having a vertical end plate 11. 20 designates the driving shaft which is shown as mounted in a frame-carried bearing 21 and embraced by a stuffing box sleeve 22 mounted in a cylindrical portion 12 of the frame. On the end of the shaft shown is keyed the impeller 30 which is shown as having a disc portion 31 bearing in a complementary recess in the frame member 11 and as carrying suitable vanes 32. The construction described is merely illustrative and may be varied greatly.

The impeller vanes 32 operate in an impeller casing 40, shown as of volute form and as having a central suction intake passageway 41 leading to the eye of the impeller and a suitable dis-

charge orifice 42. This volute impeller casing 40 is shown as an integral part of a casting providing the discharge and suction passageways and a chamber for the valve but, if desired, all of these parts may be separate casings secured together.

In the form shown, the liquid passageway to the pump comprises a suction chamber 44 leading from the suction inlet 45, preferably as high as the top of the impeller, thence leading downwardly and inwardly at 46 to the eye of the impeller. The casting provides a discharge chamber 47 into which the orifice 42 empties, which discharge passageway is shown as terminating above in a discharge orifice 48 and as continuing downwardly below the suction conduit 41 into the space designated 49.

50 and 51 designate the outer wall of the discharge chamber. The wall 50 leads downwardly from the discharge orifice 48 until it merges with the suction conduit 41 while the wall portion 51 continues downwardly to the base of the chamber portion 49. A suitable barrel-like wall 53 connects with the walls 50 and 51 at the outer edge and with walls 54 and 55 at the inner edge. 25 These inner walls terminate in the same vertical plane where they abut the vertical face of the pump member 11 to which they are bolted. One of such bolts is shown at 60 and there is preferably an interposed gasket 61 between these parts.

30 The recirculating valve is carried in a chamber 70 of its own shown as provided by the same casting which provides the suction and discharge chambers. Figs. 1 and 3 show rigid extensions 35 of the outer walls of these chambers furnishing a wall 72 of general conical form which at its upper end continues at a sharper angle and merges with horizontal under portion of the suction conduit 41 and on the vertical side with the wall 51. At the outer end of the conical portion 40 72 the walls are flanged inwardly at 73 to provide a flat face having a central opening. Mounted in this opening is the casing 80 of the recirculating valve, which I will now describe.

45 The casing 80 has at its outer end an annular flange 81 lying against the frame wall 13. Then the casing is shown as extending inwardly in a conical form at 82 to a partition portion 83. Beyond the partition the casing wall extends at 50 84 as a cylindrical member. This cylindrical member is mounted within a cylindrical flange 15 of the general casting.

55 90 designates a cap secured to the flange 81 of the valve, and 92 a diaphragm having its peripheral margin between the cap and flange, the cap and diaphragm being clamped in place by suitable cap screws 94. Clamped to the diaphragm by internal and external plates 95 is a fitting 96 to which is pivoted a rod 97 carrying 60 the valve. The rod 97 is shown as extending

through a suitable guiding bushing carried by the partition 83.

The movable portion of the valve comprises a sleeve 100 having an internal spider 101 in which the end of the rod 97 is threaded, so that the rod, when operated by the diaphragm to which it is attached, may operate the sleeve. A suitable spring, which may be a helical compression spring 110, is mounted between the diaphragm and cap 90 and tends to maintain the sleeve valve in the position shown in Fig. 1.

Extending through the wall of the valve cylinder 84 are openings 120 communicating with the annular valve chamber 70. The drawing shows a suitable conical screen 121 surrounding the openings 120. An opening 125 through the wall 51 connects the general discharge chamber with the valve chamber. Likewise an opening 126 connects the valve chamber with the suction conduit 46, and is formed and positioned to make a nozzle directed toward the eye of the impeller.

There is also an opening 128 through the head portion 82 of the valve casing into the space between the partition 83 and the diaphragm.

It results from the construction described that when the valve parts are in the position shown in Fig. 1, there is an open passageway from the discharge chamber 47 and its lower portion 49 through the opening 125 to the valve chamber and thence through the openings 120 to the interior of the valve cylinder and then axially through the valve and the passageway 126 to the suction conduit 46. This passageway, however, is closed whenever the valve is in the position shown in Fig. 3, where the sleeve bridges the openings 120 and interrupts the passageway.

I prefer to provide a self-closing valve at the suction intake 45. As shown in Fig. 1, this is provided by an annular member 130 carrying a disc valve 131 hinged to the annular member at 132, and coacting with the inner face thereof. 135 indicates an annular member internally threaded for the attachment of the suction pipe. These two annular members are secured together upon an interposed gasket 136 and such parts secured to the pump casing upon an interposed gasket 137 by suitable cap screws 138.

Describing the operating of the parts shown, and assuming that the pump is standing after having been used, there will be water in the suction passageway 46 below the suction valve chamber and the valve will be open as shown in Fig. 1. Now when the pump starts this water primes the pump, and the rotation of the impeller carries water from the suction passageway through the orifice 42 of the volute casing into the upper portion of the discharge chamber 47 and its lower portion 49. Some of this water passes through the ports 125 and 120 into the interior of the valve and thence through the passageway 126 into the suction passageway 46. There is thus a recirculation from the discharge chamber into the suction chamber and this continues to supply liquid to the impeller even though air may be drawn in with the incoming liquid through the suction passageways.

When the air is exhausted and uninterrupted liquid is in the various passageways, the pressure developed in the discharge passageway acts through the opening 128 in the head portion of the valve casing against the upper face of the diaphragm 92. This pressure overcomes the force of the spring 110 and moves the diaphragm toward the cap 90, which results in the valve being

10 moved along its seat and over the openings 120 to close the same, the valve thus coming into the position shown in Fig. 3.

15 The closing of the valve by the pressure in the discharge chamber shuts off the recirculation of the liquid, and thereafter the pump operates to receive liquid from the suction passageway 46 and discharge the entire amount to the delivery pipe without loss by reason of recirculation.

10 If at any time during the operation of the pump, air reaching the impeller interferes with the impeller throwing a solid stream of water, the resulting diminution in pressure in the discharge chamber relieves the pressure through the opening 128 against the diaphragm and the spring 110 thereby moves the diaphragm and valve to open the ports 120. This enables circulation from the discharge chamber to the suction chamber and results in the priming being reestablished.

15 It will be noticed that the passageway 126, which as heretofore stated forms a nozzle, discharging toward the eye of the impeller, is comparatively close to the impeller, so that a small amount of liquid coming through this passageway may be effective in priming the pump. The passageway 126 is quite small in comparison with the suction intake 45 and hence there is little loss in the negative pressure built up by the pump to effect the suction even when the port 120 is open.

20 It will be seen from the above description that my valve operation is entirely automatic. When the pump is operating normally the valve maintains the recirculation passageway closed so that the pump may operate at maximum efficiency. Whenever needed for priming the condition which causes such need also causes the valve to open, so that priming automatically takes place.

25 It will be further seen that by reason of the sleeve valve shown the valve is not subjected to improper action resulting from the vacuum or reduced pressure in the suction passageway. If the rotating impeller should draw fluid faster than the same can be supplied through the suction opening, or should the suction valve fail to open, this reduced pressure does no harm since the open sleeve of the valve allows the same pressure to exist on each end thereof and hence the valve situation as controlled by the discharge pressure is not changed.

30 Pumps of this type are frequently used for drawing up water for a considerable height and simply allowing it to spill over from the discharge chamber as, for instance, in draining sumps, mines, etc. Accordingly, there is liable to be very little positive head pressure on the discharge side while there may be a decided negative pressure on the suction side. On the other hand, the situation may be reversed and the pump may draw water from a low level and deliver it to a considerable height, thus causing comparatively great positive pressure and a small negative pressure.

35 My control valve is designed to meet such varying situations by being independent of the pressure conditions in the suction line. Hence, excessive suction has no effect in tending to seat the valve and shut off the priming water. By making the spring 110 light enough a very small pressure head may be sufficient to seat the valve in opposition to such spring.

40 Moreover should dirt or other foreign matter get past the screen 121 into the interior of the valve, this does no harm as the same can pass readily through the valve and thence be dis-

charged through the opening 126 into the suction chamber.

My valve is simple in construction, there is nothing about it to get out of order and it may be readily mounted in place in its chamber and thus in communication with both the discharge and suction passageways. On the other hand, the valve may be readily removed whenever it is desired to clean the embracing screen or for any other purpose.

I claim:

1. In a pump, the combination of an impeller, a casing therefor having a suction orifice and a pressure discharge orifice, a conduit leading to said suction orifice, a conduit for pumped liquid leading from the pressure discharge orifice, a return passageway from the pressure conduit terminating in a nozzle discharging into the suction conduit toward the impeller, said nozzle being of comparatively small bore in comparison with the admission opening to the suction conduit, and means controlled by the pressure in the pressure conduit for closing said return passageway when priming liquid is not needed.

2. In a pump, the combination of an impeller, a casing therefor having a side inlet and a discharge outlet, a suction conduit leading to the side inlet, and a conduit for pumped liquid leading from the discharge outlet, a return passageway from the pressure conduit terminating in a nozzle discharging into the suction conduit toward the eye of the impeller, and means controlled by the static pressure above atmospheric pressure in the pressure conduit and independent of the suction in the suction conduit for closing said return passageway when priming liquid is not needed.

3. In a pump, the combination of an impeller, a suction inlet conduit and a discharge conduit, a passageway for recirculating liquid from the discharge side of the impeller to the suction side, and a device for controlling said passageway having a cylinder with a port and a slidable hollow sleeve within the cylinder adapted to close the port, said port and said sleeve when not covering the port forming a portion of said passageway, and a diaphragm subjected to the pressure of the discharged liquid and adapted to operate the sleeve.

4. In a pump, the combination with an impeller of means defining a suction passageway leading to the impeller and a discharge passageway leading from the impeller, a valve chamber in communication with the discharge passageway, a valve casing in said chamber having a barrel with a port through it, an open-ended sleeve valve in the barrel adapted to close the port or provide a communication from the port through said sleeve to the suction passageway, and pressure control means for operating the valve.

5. In a pump, the combination, with an impeller, of means defining a suction passageway leading to the impeller and a discharge passageway leading from the impeller, a valve chamber in communication with the discharge passageway, a valve casing in said chamber having a barrel with a port through it, an open-ended sleeve valve in the barrel adapted to close the port or provide a communication from the port

5 through the valve sleeve to the suction conduit, a diaphragm, a rod connecting the diaphragm to the valve sleeve, a spring acting against one side of the diaphragm and tending to move the valve to open position, and means for admitting pressure fluid from said valve chamber to the interior of the valve case to act against the other side of the diaphragm to close the valve.

6. A pump having a suction chamber and a discharge chamber, a valve construction comprising a valve casing having a body and a cylinder separated by a partition, there being a port through the wall of the cylinder in open communication with the discharge chamber, an open ended sleeve valve in the cylinder adapted to cover or uncover said port and having its interior in communication with the suction chamber, a rod for operating the sleeve valve connected to it and passing slidably through the partition, a diaphragm across the body of the valve casing and connected to the rod, a spring tending to move the diaphragm in one direction, and a port through said casing body adapted to admit fluid from the discharge chamber to the space between the diaphragm and partition, to move the diaphragm in the opposite direction.

7. In a pump, the combination, with means providing a discharge chamber and a suction chamber, of a valve chamber in open communication with the discharge chamber, a valve in said valve chamber including a valve casing having a substantially conical head, a cylindrical portion and a partition between them, a port through the wall of the cylinder in communication with the valve chamber, a port through the head in communication with the valve chamber, a diaphragm across the head, a cap clamping the diaphragm against the head, a helical spring between the cap and diaphragm tending to move the diaphragm toward the partition, a sleeve valve in the cylinder, a rod passing through the partition and connecting the sleeve valve with the diaphragm, a port through the head of the valve casing between the diaphragm and partition, whereby pressure in the valve chamber may operate the diaphragm in opposition to the spring to move the valve across the port of its cylinder, the space within the valve communicating with the suction chamber of the pump, whereby diminished discharge pressure in the pump results in a recirculation of the liquid from the discharge chamber through the valve to the suction chamber.

8. A pump having a suction chamber and a discharge chamber, a removable valve casing inserted in a region in open communication with the discharge chamber, said valve casing having a body portion with an annular flange by which it is secured in place and with a cylindrical portion and a partition between the body and cylindrical portion, a sleeve valve in the cylindrical portion controlling a port through the wall thereof, and having it interior in communication with the suction chamber, a screen surrounding the valve casing and secured thereto outside of said port, a diaphragm within said casing connected with the sleeve valve, and means for subjecting the diaphragm to the pressure of liquid in the discharge chamber.

ALEXANDER V. MUELLER.
